SHUTTLE

Joseph T. Pospiszel, North Broadalbin, N. Y., assignor to Mohawk Carpet Mills, Inc., Amsterdam, N. Y., a corporation of New York

Application July 24, 1951, Serial No. 238,289

10 Claims. (Cl. 139—197)

1

This invention relates to selvage shuttles, such as are used in looms, in which the filling is inserted by a needle, for passing a cord through the loop of yarn carried by the needle to retain the loop in place, as the needle is withdrawn from the shed, and form the selvage. More particularly, the invention is concerned with a novel selvage shuttle, which is superior to such shuttles as heretofore made in numerous respects. The new shuttle is easier to thread up than conventional shuttles and the replacement of an empty bobbin by a full one can be carried out more quickly in the new shuttle than in former shuttles. In addition, the new shuttle is provided with cord gripping means, which are adjustable, so that the tension on the cord can be varied, and the cord gripping means are disposed in a new location, so that the shuttle can easily be kept clean and free from lint.

Selvage shuttles, as made heretofore, commonly include an elongated slightly curved body of metal having an upwardly turned horn at its forward end. A bobbin cavity is formed in one side of the shuttle and the spindle of the bobbin is supported in a pair of bearings, one of which is rigidly attached to one end wall of the shuttle cavity, while the other is resiliently mounted at the other end of the cavity and can be separated from the first to release the bobbin spindle. A strip of spring steel is attached at one end to the inner surface of the top wall of the cavity near one end thereof and the strip has a downwardly curved portion near its free end. The curved part of the strip has an opening through it and, beyond the curved part, the strip is flat and contacts with the top inner surface of the cavity. The top wall has an opening just beyond the free end of the strip.

In prior selvage shuttles of the construction described, the end of the cord from the bobbin mounted on a spindle in the bearings must be passed first through the opening in the curved part of the strip, then between the flat end section of the strip and the top inner surface of the cavity, and finally out through the opening in the top wall of the cavity. Such a threading-up operation is difficult because of the stiffness of the strip and the inaccessibility of the openings and it is also difficult to release the bobbin spindle from its bearings. As a result, replacement of an empty bobbin in the shuttle by a full one is time consuming. Another objection to the prior shuttle is that the space between the curved section of the strip and the top inner surface of the cavity collects lint, which cannot be easily removed. All these objectionable fea-

tures contribute to loss of production of looms, in which the shuttles described are used.

The selvage shuttle of the invention avoids the disadvantages of the former construction and can be easily refilled and threaded up and also kept clean. In the preferred form of the new shuttle, the cord gripping device is mounted on the top surface of the shuttle, so that it is fully accessible, and the cord passes from the bobbin to the device through a slot in the top wall of the bobbin cavity having an entrance opening in the free edge of that wall. The device is also adjustable, so that the tension on the cord may be varied as desired, and, because of its accessibility and the use of a guide slot for the cord, instead of a hole, the shuttle can be easily kept clean. The preferred form of the shuttle is also provided with means for retaining the bobbin spindle, which are automatic in action and release the spindle, when the shuttle is turned upside down.

For a better understanding of the invention, reference may be made to the accompanying drawing, in which:

25 Figs. 1 and 2 are front elevational and top plan views, respectively, with parts broken away, of selvage shuttles as heretofore commonly constructed;

Fig. 3 is a front elevational view of one form of the selvage shuttle of the invention;

30 Fig. 4 is a plan view, with parts broken away, of the shuttle shown in Fig. 3;

Fig. 5a is a sectional view on the line 5a—5a of Fig. 3;

35 Figs. 5b and 5c are views similar to Fig. 5a, showing the shuttle being rotated on its longitudinal axis;

Fig. 6 is a sectional view on the lines 6—6 of Fig. 4;

Fig. 7 is a view similar to Fig. 5a, showing 40 a modified construction; and

Fig. 8 is a front elevational view of another form of the new shuttle.

The conventional selvage shuttle illustrated in Figs. 1 and 2 comprises an elongated metal body 45 having a flat bottom surface 11, which rests on the bottom of the shuttle raceway. At its forward end, the body is formed with an upwardly curved horn 12, and the front and rear surfaces 13, 14 of the body are curved with an approximately concentric curvature corresponding to that of the shuttle raceway. The shuttle is reciprocated in the raceway by a rocker arm having fingers at its free end, one of which enters a notch 15 in the top of the shuttle near its forward end and the other of which engages

the curved upper portion 16 of the rear end of the shuttle.

The shuttle is provided with a cavity 17 open through its front face for holding a bobbin 18 wound with the selvage cord 19. The bobbin is mounted on a spindle 20, one end of which is received in a bearing 21 rigidly attached to the rear wall of the cavity. The other end of the spindle is supported in a bearing 22 held in position by a spring, which can be compressed to move bearing 22 away from bearing 21 sufficiently to release the spindle.

The cord 19 is maintained under tension by means of a gripping device consisting of a spring strip 23, which is secured by a screw 24 against the inner surface of the top of cavity 17. Between the screw and its free end, the strip has a downwardly depressed portion 23a having an opening 23b for passage of the cord and the top wall of the cavity has an opening 25 just beyond the free end of the strip.

With the conventional shuttle construction described, the threading-up of the shuttle requires that the end of the cord be passed through opening 23b through the spring strip, and then led along the inner surface of the top wall of the cavity and between that wall and the strip to opening 25. As the strip is very stiff, it is difficult to thread the cord through the openings and between the strip and the wall of the cavity and this operation consumes a considerable amount of time. Also, the shuttle is not provided with any means for regulating the grip of the strip on the cord and the shuttle is difficult to keep clean because lint accumulates in the space between the downwardly curved section 23a of the strip and the top wall of the bobbin cavity.

The preferred form of the shuttle of the invention shown in Fig. 3 includes a body 26 generally similar to the body 10 of the prior shuttle. The body is formed with a bobbin cavity 27 opening through the front wall of the body, and, at opposite ends of the cavity, the body is formed with a pair of horizontal slots 28 leading inward from its front face. The slots lie in the axis of the cavity and are adapted to receive the ends of a spindle 29, on which the bobbin 30 is mounted. Each slot 28 is intersected by a chamber illustrated as having the form of a vertical bore 31, which leads inward from the bottom surface of the body and contains a pin 32 held in place by a screw 32a threaded into the bore. The construction is such that, when the shuttle is in upright working position, the pins 32 in the bores 31 extend across slots 28 to confine the ends of the spindle 29 behind them in the slots. When the shuttle is turned upside down to the position shown in Fig. 5c, the pins 32 slide up into the upper ends of the bores, so that slots 28 are no longer closed by the pins and the spindle 29 with the bobbin thereon is free to slide out of the slots. Accordingly, when an empty bobbin is to be replaced by a full one, the shuttle is merely inverted, the spindle and bobbin removed, a full bobbin placed on the spindle, and the ends of the spindle inserted into slots 28 and held against the inner ends thereof. By then turning the shuttle right side up, pins 32 drop down to close the slots and hold the spindle in position.

In order to maintain the cord being supplied from the bobbin under tension, the shuttle is provided with a cord gripping device, which comprises a disc 33 mounted on top of the shuttle and held in place by a screw 34 passing through an opening in the disc and threaded into the top of the body above the bobbin cavity. The screw

has a domed head 35, the periphery of which is formed with notches 35a. A coil spring 36 is interposed between the head 35 and the top of disc 33 and urges the disc toward the top surface of the body with a force dependent on the extent to which the screw is threaded into the body. The screw is held in the desired position of angular adjustment by a pin 37 mounted in a bore in the body and urged by a spring 38 into the adjacent notch 35a on the head of the screw.

A passage is formed through the top wall of the bobbin cavity and the passage is illustrated as having the form of a slot 39, which leads inward from the free edge of the wall and has a branch 39a extending beneath disc 33. Preferably, the body is thickened near its forward end to form an upward projection 40 lying ahead of the tension device and provided with a curved vertical shoulder 41 lying close to and extending above the forward edge of the head 35 of screw 34.

In threading up the new shuttle, the cord from the bobbin is passed into slot 39 and then into the branch 39a of the slot, after which the cord is drawn beneath the edge of disc 33. The disc 33 clamps the cord against the top surface of the body under the pressure of spring 36 and the gripping action can be varied by pushing back pin 37 against the spring 38 and turning the screw 34 in or out by means of its head 35. Although the gripping device lies on the outer surface of the shuttle, so that one of the strands of the loop of filling yarn inserted by the needle passes over the tension device in the forward movement of the shuttle, the formation of the body with projection 40 and shoulder 41 extending up above the notched edge of the head 35 of screw 34 causes the yarn to slide off the surface of the projection and over the head of the screw without being caught by the gripping device.

In the shuttle shown in Figs. 3-6, inc., the bobbin spindle 29 is held in place by pins 32, but, if preferred, the pins may be replaced by balls 42, which lie in bores 43 intersecting slots 44 leading inward from the front face of the body of the shuttle at the ends of the bobbin cavity. The balls function in the same manner as the pins in that, when the shuttle is in upright position, the balls close the slots 44 and prevent accidental displacement of the bobbin spindle 45. When the shuttle is inverted, the balls pass out of the slots and into the ends of the bores, so that the spindle can be freely removed from the slots.

The construction shown in Fig. 8 is similar to that shown in Fig. 3-7, inc., except that the bobbin spindle 46 is mounted in conventional bearings 47 and 48. Bearing 47 is fixed in position, while bearing 48 is held in place by a spring, which can be compressed to separate the two bearings sufficiently to release the spindle. In the Fig. 8 construction, the top wall of the bobbin cavity 49 is provided with a slot 50 extending inward from the free edge of the wall and serving to guide the cord 51 from the bobbin beneath the disc of a tension device 52, which is of the same construction as that employed in the new shuttle above described.

The formation of the new shuttle with the tension device in readily accessible position on its top surface and with the slot open at its outer end for guiding the cord from the bobbin to the tension device greatly simplifies the threading-up of the shuttle and makes it possible to keep the shuttle clean without difficulty. The tension can be adjusted, as described, by turning the screw of the tension device in or out and

the provision of the locking pin entering a notch in the edge of the head of the screw insures that the selected tension will be maintained until changed. The use of the preferred mounting for the bobbin spindle, including the slots and the pins or balls, which lock the ends of the bobbin spindle in place and automatically release the spindle upon inversion of the shuttle, simplifies and expedites the changing of bobbins.

I claim:

1. A selvage shuttle, which comprises an elongated body having a bobbin cavity open through a side surface of the body, a passage through the top wall of the cavity, and cord gripping means mounted on the outer surface of said top wall and including a member movable toward and away from said surface, and a spring urging the member toward said surface.

2. A selvage shuttle, which comprises an elongated body having a bobbin cavity open through a side surface of the body, a passage through the top wall of the cavity, and cord gripping means mounted on the outer surface of said top wall and including a member movable toward and away from said surface, a spring urging the member toward said surface, and an element adjustable to vary the pressure of the spring on the member.

3. A selvage shuttle, which comprises an elongated body having a bobbin cavity open through a side surface of the body, a passage through the top wall of the cavity, and cord gripping means mounted on the outer surface of said top wall and including a perforated member movable toward and away from said surface, a screw passing through the member and threaded into said top wall, and a spring engaging the head of the screw and the member and urging the member toward said surface.

4. A selvage shuttle, which comprises an elongated body having a bobbin cavity open through a side surface of the body, a passage through the top wall of the cavity, and cord gripping means mounted on the outer surface of said top wall and including a member movable toward and away from said surface, a spring urging the member toward said surface, a screw threaded into said top wall and engaging said member, the screw being rotatable to vary the pressure of the spring on the member, and means for locking the screw in adjusted position.

5. A selvage shuttle, which comprises an elongated body having a bobbin cavity open through a side surface of the body, a passage through the top wall of the cavity, and cord gripping means mounted on the outer surface of said top wall and including a member movable toward and away from said surface, a spring urging the member toward said surface, a screw threaded into said top wall and engaging said member, the screw being rotatable to vary the pressure of the spring on the member and having a head formed with a series of notches, and a spring-pressed pin engageable in any of said notches to hold the screw in adjusted position.

6. A selvage shuttle, which comprises an elongated body having an upwardly curved horn at its forward end and a bobbin cavity open through a side surface of the body, the top surface of the body having a transverse shoulder adjacent its forward end, a slot in the top wall of the cavity to the rear of the shoulder and having an en-

trance opening at the free edge of said wall, and cord gripping means mounted on the outer surface of said top wall to the rear of and adjacent to the shoulder.

5 7. A selvage shuttle, which comprises an elongated body having an upwardly curved horn at its forward end and a bobbin cavity open through a side surface of the body, the top surface of the body having a transverse shoulder adjacent its forward end, a slot in the top wall of the cavity to the rear of the shoulder and having an entrance opening at the free edge of said wall, and cord gripping means mounted on the outer surface of said top wall to the rear of and adjacent to the shoulder, said means including a spring-pressed element and a screw threaded into the top of the body and rotatable to vary the position of the element, the screw having a head lying close to the shoulder.

10 8. A selvage shuttle, which comprises an elongated body having a bobbin cavity open through a side surface of the body, means at the ends of the cavity for holding the spindle of a bobbin, a slot in the top wall of the cavity having an entrance opening at the free edge of said wall, and cord gripping means mounted on the outer surface of said top wall and adapted to grip a cord passing out of the cavity through the slot.

15 9. A selvage shuttle, which comprises an elongated body having a bobbin cavity open through a side surface of the body, a pair of slots leading inward through said side surface at opposite ends of the cavity, a chamber intersecting each slot, an element within each chamber adapted to move within the chamber to a position, in which it closes the related slot, when the shuttle is moved to upright position, a passage through the top wall of the cavity, and cord gripping means mounted on the outer surface of said top wall and adapted to grip a cord passing out of the cavity through the passage through said top wall.

20 10. In a selvage shuttle, a body having a bobbin cavity open through a side surface of the body, a pair of slots leading inward through said side surface at opposite ends of the cavity and open to the cavity, a substantially vertical bore in the body intersecting each slot, and an element in each bore shorter than the length of the bore and 25 movable in its bore, as the shuttle is moved to upright position, to a position, in which the element closes the related slot, the element moving to a position wholly within the bore to open the related slot, as the shuttle is inverted.
